UNITED STATES PATENT OFFICE.

CHARLES HARKNESS, OF PROVIDENCE, RHODE ISLAND, ASSIGNOR TO HENRY C. DEXTER, OF CENTRAL FALLS, RHODE ISLAND.

HOOK AND EYE.

1,112,904.

Specification of Letters Patent.

Patented Oct. 6, 1914.

Application filed July 11, 1910. Serial No. 571,361.

To all whom it may concern:

Be it known that I, CHARLES HARKNESS, a citizen of the United States of America, residing at Providence, in the county of Providence and State of Rhode Island, have invented certain new and useful Improvements in Hooks and Eyes, of which the following is a specification, reference being had therein to the accompanying drawing.

Similar letters of reference indicate corresponding parts in all the figures.

My invention relates to an improvement in hooks and eyes and has for its object the overcoming of the hereinafter enumerated various defects in, and objections to, the hooks and eyes in common use and comprises the novel construction and combination of the several parts as hereinafter described and particularly set forth in the claim.

Figure 1 shows in elevation one form of my improved hook with an eye in engagement therewith. Fig. 2 is a side elevation of the same. Fig. 3 shows a portion of a cloth garment, which has the same applied to the meeting edges thereof, the overturned edge of the fabric being broken away at the third hook from the end. Fig. 4 shows in elevation another form of my improved hook. Fig. 5 is a side elevation thereof. Fig. 6 shows a portion of a lace garment which has the form of hook shown in Fig. 4 and an eye applied to the meeting edges thereof. Fig. 7 shows in elevation an eye. Fig. 8 is a side elevation thereof. Fig. 9 is an elevation of another form of my improved hook. Fig. 10 is a side elevation thereof.

In the drawings A represents my improved hook, which has the sewing eyelets $a a$ and $a' a'$ and the tongue T, all in the same plane. The eyelets are formed at both ends of parallel side-bars and the tongue T is supported by connections extending to two of said eyelets forming shoulders disposed back of the edge eyelets a, a , and supports for said tongue which extend substantially parallel to said side bars. The spread of the tongue T at its maximum width is equal to or a little wider than the space between the sides of the eye B. Thus when the tongue is made wider than the eye the sides of the eye are sprung apart slightly as it passes the place where the tongue is the widest and

then the sides recover their normal position and serve as a locking means against the accidental unfastening.

The connections which form the eye supporting shoulders and the tongue supports provide relatively long connections or supports for the tongue, thereby allowing of its bending out of alinement to facilitate the easy engagement of the eye-member and further reinforce the edge of the material and retain it smooth and flat.

The eye B has the sewing eyelets $b b$, and the end c is bent or curved out of the plane of the rest of the eye. The curvature at the end c may be as much or as little as desired, according to the thickness of the fabric, which is designed to occupy this curved seat, the sewing eyelets $b b$ being on the under side and the engaging bar at c projecting out just enough to allow of the free engagement of the tongue T therewith. However any form of eye, or loop, or bar, may be used with my improved hook, as desired.

In the use of my improved hook, as seen in Figs. 3 and 6, the sewing eyelets $a a$ are at the very edge of the garment and in advance of the tongue of the hook. The edge of the garment may be turned over upon and cover the sewing eyelets $a a$, or the hook may be merely attached to the garment, as appears.

My improved hook may be so attached to a garment that the sewing eyelets would hold the fabric tightly against the tongue T, so that any eye engaged therewith would be so bound and constrained by the fabric that this of itself would serve as a means against accidental unfastening.

Heretofore hooks have usually been so constructed that all parts thereof do not lie in a common plane at all times and under all conditions as does my improved hook, but rather some parts are either bent upon themselves as for instance is the tongue of the hook most commonly used, or humps are formed, or parts are bent to allow for the engagement with the eye. The result is that in such cases by repeated ironing and pressing the hook becomes almost useless and inoperative by the tongue being jammed into close contact with the adjacent parts, or by reason of the parts that lie outside of the common plane becoming flattened down. Inasmuch as all parts of my improved hook are at all times in one and the same plane

continued pressing and ironing of the same and of the garment to which it is attached will not in any way injure their construction or operativeness, or render them less liable to engage freely with the eye.

In the old form of hook and eye the sewing eyelets of any one hook are quite close together relative to the distance of the hooks one from the other so that in the case of well 10 made, close fitting garments the fabric is drawn and pulled at these fixed points not only causing the garment to gap open but to pucker and bulge out on a line across the body of the wearer between the lines of 15 stress or pull as aforesaid.

In the case of my improved hook the pull is not so concentrated but is dispersed and more evenly distributed causing a uniform pull along the entire length of the edge of 20 the garment and this too without requiring a large number of hooks placed closely together and also at the same time holding the surface of the garment flat, even and against bulging by reason of the large area of the 25 fabric confined within the limits of the out-lying sewing eyelets of my improved hook.

When in the use of old forms of hooks and eyes where on an overlapping edge the attaching points of either the hooks or the 30 eyes are back from the edge of the garment the pull comes down along the line of said attaching points, which line is a little way back from said edge thus making a strip of the garment along the edge that is either 35 loose or at best badly secured and often becomes folded back and gaps and exposes the hook and eye to view. In the use of my im-

proved hook part of the sewing eyelets, namely *a a*, are upon the very outer edge of my overlapping edge, as seen in Figs. 3 and 40 6, and the seat or point of engagement of the eye with the base of the tongue of the hook is at a point farther back or away from said overlapping edge than are the sewing eyelets *a a*. Whereby said overlapping edge is 45 positively, firmly, evenly and flatly held out over the underlying edge and the eyelets B, B, thereon effectively concealing the same from view and at all times presenting a neat and trim appearance. 50

I claim as a novel and useful invention and desire to secure by Letters Patent.

A device of the character described, embodying a hook member comprising parallel side-bars spaced apart and provided with 55 sewing eyelets at both ends, two of said eyelets adapted to be secured at the edge of the material to which the hook is attached, a tongue disposed between said side-bars, and connections extending between the base of 60 said tongue and two of said eyelets forming shoulders back from said edge eyelets and supports for the tongue which extend substantially parallel with said side-bars, 65 all and every part of said elements lying in the same plane, and an eye-member adapted to snap over said tongue and engage said shoulders.

In testimony whereof, I affix my signature hereto in presence of two witnesses.

CHARLES HARKNESS.

In presence of—

FRANK BARNBROOK,

HOWARD A. LAMPREY.
